PIPE FORMING MACHINE

Herman L. Moor, Olive Township, St. Joseph County, Ind.

Application May 31, 1943, Serial No. 489,109

21 Claims. (Cl. 25—32)

1

This invention relates to a pipe forming machine.

The primary object of the invention is to provide a machine for simultaneously making and laying in a trench a continuous and jointless pipe formed of concrete or other plastic material.

A further object is to provide a machine of this character with means for incorporating reinforcing material within a pipe as the same is formed.

A further object is to provide a machine of this character for compacting backfill around a form in advance of the pipe-making and laying operation, whereby said compacted backfill constitutes the outer form for the pipe.

A further object is to provide a machine of this character with means for vibrating the plastic material while the same passes from feed means to molding forms thereof.

A further object is to provide a device of this character having an elongated flexible inner form trailing therebehind to provide an interior support for the fresh-laid pipe during the period the same is setting to shape.

A further object is to provide a machine of this character which is self-propelling.

A further object is to provide a machine of this character with a rotating and vibrating cylinder mounting a screw to feed plastic to and compact it in an annular mold cavity, said cylinder constituting part of an inner pipe mold.

Other objects will be apparent from the drawings, description and appended claims.

In the drawings:

Fig. 1 is a top plan view of the machine with parts shown in longitudinal transverse section taken on line 1—1 of Fig. 2.

Fig. 2 is a longitudinal vertical sectional view taken on line 2—2 of Fig. 1.

Fig. 3 is a vertical transverse sectional view taken on line 3—3 of Fig. 2.

Fig. 4 is a vertical transverse sectional view taken on line 4—4 of Fig. 1.

Fig. 5 is a vertical transverse sectional view taken on line 5—5 of Fig. 2.

Fig. 6 is a vertical transverse sectional view taken on line 6—6 of Fig. 2.

Fig. 7 is a side view of the vibrating inner cylinder of the machine.

Referring to the drawings, which illustrate the preferred embodiment of the invention, the numeral 10 designates the frame or body of the machine. Frame 10 is formed of rigid metal plate material and comprises vertical side walls 11, an arcuate bottom 12, and an arcuate front 13, said bottom and front merging in a curved portion 14.

2

An arcuate longitudinal wall 15 concentric with bottom 12 extends from a point intermediate the ends of the frame to the rear of the frame and merges with a cylindrical portion 16 projecting rearwardly from the frame. The outer diameter of portion 16 conforms with the outer diameter of the pipe to be formed. A vertical chute or passage 17 projects upwardly from wall 15 and communicates with a hopper 18 which is secured to and supported by the rear end of walls 11 at its upper end.

Two or more cross bars 19 are secured to and extend transversely between the walls 11 adjacent the front thereof and an internal combustion engine 20 or other drive means is mounted thereon by any suitable mounting members 21. Drive shaft 22 of the engine projects rearwardly therefrom and is journaled at its end in a bearing 23 carried by a cross bar 24 extending transversely between and secured to the side walls 11.

A pinion 25 is keyed to shaft 22 and meshes with a gear 26 therebelow keyed to a shaft 27. The shaft 27 is journaled in a bearing 28 supported by a cross bar 29 extending between and secured to sides 11. A second bearing 30 mounted on a bracket arm 31 supported at the front end of wall 15 also journals shaft 27. A bevelled pinion 32 is mounted on the rear end of shaft 27 and meshes with a bevel gear 33 keyed to a transverse shaft 34. The ends of shaft 34 are mounted in openings formed in side walls 11 and spanned by plates 35 secured to the outer faces of said walls. Shaft 34 is journaled in bearings 36 supported by vertical bracket arms 37, Fig. 3, projecting upwardly from wall 15 and by longitudinal bracket arms 38 projecting forwardly from chute 17. Adjacent the opposite ends thereof, shaft 34 has circular cams 39 mounted eccentrically thereon and keyed thereto and encircled by rings 40 mounted on the forward ends of a pair of bars 41 extending longitudinally at opposite sides of chute 17. Bars 41 mount a transverse ramming plate 42 at their rear ends and adjacent and rearwardly of the rear ends of side walls 11. The plate 42 is of a width slightly less than the width of frame 10, and has a concave arcuate lower edge 43 whose radius is slightly greater than the radius of the outer periphery of frame cylinder 16 upon which the lower central portion of said plate 42 bears in spaced relation to the rear end of said cylinder.

A wide annular bearing 44 is mounted at the forward end of the annular space defined by frame bottom 12 and wall 15, said bearing preferably comprising an outer raceway 45 and an

inner raceway 46. The outer raceway 45 is secured to the rear end of wall 15 and the inner raceway 46 is secured to the front end of frame bottom 12. The inner raceway 46 is journaled in a bearing 47 supported by a bracket arm 48 secured to the front end of wall 15. The inner raceway 46 is journaled in a bearing 49 supported by a bracket arm 50 secured to the front end of frame bottom 12.

inner raceway 46, each having two or more spaced registering circumferential grooves receiving hard metal bearing balls 47, and end retainer rings 48 suitably constructed to seal oil therein and exclude plastic. A cylinder 49 is journaled in bearing 44 adjacent its front end.

Cylinder 49 is best illustrated in Figs. 2 and 7, and its outer diameter is equal to the inner diameter of the pipe to be formed. The cylinder is elongated to project rearwardly from the cylinder 16 at 50 and to project forwardly of wall 15 at 51. A helical external feed screw 52 is carried by the central portion of cylinder 49, extending from bearing 44 to a point substantially coincident with the rear end of frame cylinder 16. The screw 52 is of a diameter less than the inner diameter of cylinder 16. Two or more spaced longitudinal ribs 53 are secured within cylinder 16, said ribs being of a thickness to be engaged by screw 52 to form supports for the cylinder rearwardly of bearing 44. The rear end of cylinder 49 is provided with a closure plate or spider 54 having a central aperture 55 therein. A closure plate 56 is removably mounted on the front end of cylinder 49 and has a central bearing 57. A disc 58 is fixedly mounted within the cylinder intermediate the ends thereof and has a central bearing 59. A shaft 60 having a central bore 61 therethrough is journaled in bearings 57 and 59, and projects forwardly from the cylinder. An unbalanced arm 62 is fixedly secured on shaft 60 adjacent disc 58. A pair of abutment rings 63 are secured to shaft 60 on opposite sides of bearing 57 to prevent relative endwise movement of the shaft and cylinder. The portion of cylinder between disc 58 and closure plate 56 may contain cooling fluid, such as oil.

A pulley 64 is mounted on engine shaft 22 forwardly of pinion 25, and a pulley 65 is mounted on the forwardly projecting end of shaft 60. A belt 66, preferably a V-belt, is trained around said pulleys to rotate shaft 60 and unbalanced arm 62 at comparatively high speed, thereby causing said shaft and the cylinder to vibrate.

The forward projecting end portion 51 of cylinder 49 mounts an annular sprocket 67, and a sprocket 68 is mounted on shaft 27 intermediate bearings 28 and 30. A chain 69 is trained around said sprockets to rotate cylinder 49. It will be noted that the cylinder 49 is rotated at a low speed compared with the rate of rotation of shaft 60, by virtue of the speed reduction effected through gears 25 and 26 and through sprockets 67 and 68.

An elongated flexible inner pipe form trails behind cylinder 49. As here illustrated, this form is made up of a plurality of articulated annular non-collapsible sections or elements 70 each of the same outer diameter as portion 50 of cylinder 49. Each element 70 has a reduced diameter portion 71 projecting from the front end thereof and fitting within the rear end of the preceding element or of the cylinder 49 with a small clearance. The rear edge of each element and the shoulder between the same and portion 71 at the front thereof, are preferably rounded or tapered at 72. The construction and interfitting relation of elements is such as to permit a limited amount of angular displacement of adjoining elements 70 to permit the same to follow a bend in a pipe. The elements 70 are interconnected by a cable 73 passing therethrough. The front end of cable 73 extends through opening 55 in rear cylinder wall 54 and fixedly mounts a fitting 74 bearing against said cylinder wall. The rear end of cable 73

extends into the rearmost element 70 and fixedly mounts a fitting 75 having a cup-shaped or annular retainer 76 against which the rear end of a tensioned coil spring 77 encircling said cable bears. A disc 78 having a small central aperture 79 fits within the rearmost element 70 and bears marginally against the internal shoulder between element 70 and reduced diameter collar 71 of said element. Spring 77 presses against the outer outer face of disc 78, and cable 73 passes freely through aperture 79. Any selected number of elements 70 may be interconnected in this manner.

A vertical boom or mast 80 is fixedly mounted at the front of frame 10, said mast being supported in a socket 81 carried by the lower portion of the front of said frame, and being positioned by retainers 82 above said socket. The uppermost retainer may include a hitch ring 83. Mast 80 preferably extends to a considerable height, and mounts brackets 84 projecting laterally and oppositely therefrom adjacent its upper end. Each bracket 84 journals a pulley 85. A pair of opposite laterally projecting brackets 86 is secured to mast 80 intermediate the height thereof. Each bracket 86 mounts a winch 87. A guy cable 88 is wound on each winch, extending upwardly around a pulley 85 and then extends laterally to an anchor spaced from the trench 89 in which the machine operates. Mast 80 is preferably of such height and the guy anchors are preferably so spaced from the trench that workmen and vehicles may pass thereunder without interference. While two guys have been illustrated and may be adequate to support the machine in vertical position in the trench, four may be used if desired by providing the necessary number of pulleys and winches therefor.

An elongated bent tube 90 having a vertical portion secured to the front of the frame at 91 and a rearwardly longitudinally extending lower portion supported by a bracket 92 is mounted within the machine frame with its rear portion terminating adjacent to and in axial alignment with shaft 60. Suitable means (not shown) may feed reinforcing wire 93 (Fig. 5) into said tube to be guided therethrough and into bore 61 of shaft 60. A second bent tube 94 has its ends secured by an L-shaped bracket 95 fixedly secured within the cylinder 49 rearwardly of disc 58, whereby one end thereof is axially aligned with bore 61 to guide wire 93 from the shaft bore to and through a hole 96 in the cylinder. As here illustrated, hole 96 extends through one of the convolutions of screw 52 at a point rearwardly of ribs 53 and adjacent the rear end of cylinder 16, whereby said wire is coiled as cylinder 49 is rotated.

One or more additional tubes or guides 97 may be mounted within the frame at the front thereof, supported by brackets, as brackets 91 and 92, for passage of longitudinal reinforcing rod stock therethrough by any suitable means (not shown). Frame 10 and wall 15 may have longitudinally spaced openings 98 and 99 therein through which such rod stock may be passed. The rearmost openings will preferably be positioned in advance of the front ends of ribs 53, so that said rod may pass therebetween to be guided longitudinally thereby.

The operation of the device is as follows: The machine is lowered into trench 89 and may be pulled along therein immediately behind a trench digging machine by any suitable means (not shown) which pulls a draw member connected to

the machine at 83, or the machine may be permitted to propel itself as hereinafter described. The guy cables 88 are connected to hold mast 89 and the machine frame in vertical position; the reinforcing wires 93 and the longitudinal reinforcing rods are threaded or guided to proper feeding position in the machine; and hopper 18 is filled with the concrete or other mix; and the machine is ready for operation. Best results are obtained by using a concrete mix containing a minimum amount of water, and the mix may also be treated to impart quick-setting properties thereto.

Upon operation of the engine 20, three operations occur, apart from the feed of the reinforcing wire and rods, namely, reciprocation of ram arms 41 and ram plate 42 by cams 39, rotation of cylinder 49 by chain 69, and rotation of shaft 60 and unbalanced arm by belt 66. Backfill 100 is continuously emptied into the trench 89, and is compacted by the ram plate 42 whose stroke terminates forwardly of the rear end of frame cylinder 16. Hence cylinder 16 constitutes an outer form around which the backfill is compacted, so that the machine forms a circular earth tunnel therebehind. Also, it will be apparent that if the backfill material is emptied into the trench continuously, the action of the reciprocating ram plate 42 pressing thereagainst will serve to propel the machine forwardly in the trench at a rate proportional to the rate at which the backfill material is fed. This action assumes, of course, that the backfill material is of a consistency to permit compacting thereof, since it will be apparent that the backfill must be finely compacted to form an abutment against which the pushing action may be exerted and also to maintain its shape after the frame cylinder passes therefrom.

The rotation of cylinder 49 serves to rotate screw 52 to feed the plastic mix rearwardly for continuous discharge into the annular cavity between the inner form and the circular cavity in the compacted backfill behind the cylinder 16. By properly correlating the rate of forward movement of the machine with the rate at which cylinder 49 is rotated, the mix is compacted in the annular receiving cavity therefor to insure uniformity and solidity of the pipe 101 being formed. Rotation of the cylinder 49 also serves to wind reinforcing wire 93 into helical form concentric with and properly positioned in the pipe wall intermediate the inner and outer peripheries thereof.

The cylinder is vibrated by the comparatively high speed rotation of shaft 60 and unbalanced arm 62 therein, and thus the plastic mix is vibrated as it is propelled in the cylinder 16 by screw 52. This also assists in the compacting and solidifying of the mix. Note that the journaling of the cylinder 49 at its forward end only provides a cylinder mounting facilitating vibration. At the same time, the provision of the longitudinal ribs 53 in the frame forms a support for the free or unjournaled end of the cylinder to limit the extent or amplitude of the vibrations and to limit the stresses applied to bearing 44 by the vibration. The high speed rotation of shaft 60 and the incident vibration generates heat, and consequently the filling of the forward end of the cylinder with a liquid, such as oil, serves as a heat transfer means to hold the heat at bearing surfaces, etc., within safe limits and to uniformly transmit the heat to the cylinder walls to heat the mix.

A concrete mix requires a certain minimum

time for setting thereof, during which time the mix must be confined within a form. This is accomplished in the instant device by the trailing flexible inner form. The length of this form which is required will depend upon various factors, including the rate at which the machine advances, the setting properties of the mix, i. e., the percentage of water contained in a concrete mix, etc., and the quantity of reinforcing metal employed. Thus the length of the trailing form used with concrete pipe may vary from a minimum of forty or fifty feet to two hundred feet or more. Note that the rotation of cylinder 49 by which the trailing form is drawn may impart a limited rotation to at least some of the elements of the trailing form, and such rotation in conjunction with the forward movement of the trailing form serves to smooth and finish the mix at the interior of the pipe as the mix is setting up, thus forming a smooth solid inner peripheral pipe surface which is a distinct advantage.

It will be apparent that the guy cables must be advanced from time to time as the machine advances, and this renders the provision of four such cables, together with automatically adjustable winches 87, an advantage inasmuch as the operation of the machine may then be continuous since the machine would not then have to be stopped for guy cable manipulation. It will be understood, however, that guy cables have been shown and described as illustrative only of one convenient means for positioning the machine, and that other positioning means may be utilized if desired.

From the above it will be apparent that the machine possesses the following distinct advantages, among others: automatic operation; manual labor or attendance is held at a low point; the machine is capable of self-propulsion; all attendants work at ground level; a strong compact jointless pipe is produced; the pipe is formed in the position at which it is to remain in use, thereby minimizing the problem of stresses incident to settling of surrounding earth; and the speed and low cost of the finished, back-filled pipe as compared to the cost of a conventional pipe line which includes the multiple factors of manufacturing cost, transportation, handling, joining and back-filling, etc.

Another feature of the machine is that it is not adversely affected if small quantities of water are present in the trench, since the mix is fed into the receiving cavity therefor between the inner form and the compacted contoured earth back-fill under pressure sufficient to force the water ahead of the rear end of frame cylinder 16, and thus prevent adverse effect thereof upon the newly poured mix.

I claim:

1. A machine for forming a pipe in a trench, comprising a frame adapted for movement in said trench and having a lower cylindrical portion, a reduced diameter cylindrical rotatable member concentric with said frame cylinder and cooperating therewith to define an annular chamber, and means for feeding plastic material to and rearwardly through said chamber into said trench, said cylindrical member including an elongated portion formed of relatively rotatable articulated sections normally in frictional end engagement adjacent their circumference projecting rearwardly from said frame to continuously interiorly support said mix while the latter sets in said trench.

2. A machine for forming a pipe in a trench,

comprising a frame adapted to be advanced in said trench and having a lower longitudinal passage, an inner form rotatable within said passage and cooperating therewith to define a tubular chamber, means for feeding plastic material to and rearwardly through said chamber into said trench, and an elongated non-collapsible flexible trailing member in torque transmitting end engagement with said rotatable form and projecting rearwardly from said frame to interiorly support said mix while the same sets in said trench, said trailing member including a plurality of articulated relatively rotatable cylindrical portions in torque transmitting end engagement.

3. A machine for forming a pipe in a trench, comprising a frame adapted to be advanced in said trench and having a lower longitudinal passage, an inner form rotatable within said passage and cooperating therewith to define a tubular chamber, means for feeding plastic material to and rearwardly through said chamber into said trench, and an elongated flexible trailing form of substantially uniform cross section including a plurality of relatively rotatable articulated rigid units connected to and in rotation transmitting engagement with the rear end of said inner form.

4. A machine for forming a pipe in a trench, comprising a frame adapted to be advanced in said trench, and having a lower longitudinal passage, an inner form within said passage and cooperating therewith to define a tubular chamber, means for feeding plastic material to and rearwardly through said chamber into said trench, and an elongated flexible trailing form of substantially uniform cross section in frictional end abutment with said inner form and including a plurality of similar rigid tubular units each having a reduced portion fitting in frictional torque transmitting relation to an adjacent unit and an elongated flexible draft member passing through said units with its opposite ends connected to said inner form and to said rearmost unit.

5. A machine for forming a pipe in a trench, comprising a frame adapted to be advanced in said trench and having a lower longitudinal passage, a cylindrical form journaled in said passage and cooperating therewith to define a tubular chamber, a feed screw in said chamber carried by said form, means for rotating said form, means for feeding plastic material into said chamber for discharge into said trench by said screw, and an elongated, flexible non-collapsible form in frictional end engagement with and drawn by said first form to continuously interiorly support said plastic material in said trench as it sets said last named form including a plurality of relatively rotatable cylindrical sections in frictional torque transmitting end to end engagement.

6. A machine for forming a pipe in a trench, comprising a frame adapted for movement through said trench and having a rearwardly projecting tubular portion, an inner form within said tubular portion defining a tubular chamber in said frame, said inner form including a uniform rearwardly trailing portion, a ram reciprocable longitudinally of said frame for packing earth around said tubular frame portion, and means for feeding plastic material to and through said chamber for discharge between said trailing form portion and said packed earth rearwardly of said frame.

7. A machine for forming a pipe in a trench, 75

comprising a frame having a rearwardly projecting tubular portion, a rotatable inner form within said tubular portion defining a tubular chamber, means for rotating said form, an external feed screw on said inner form, plastic feed means communicating with said chamber, and a longitudinally shiftable ram for packing earth around said tubular frame portion.

10 8. A machine for forming a pipe in a trench, comprising a frame having a rearwardly projecting tubular portion, an inner form in said tubular portion cooperating therewith to define a tubular chamber, means for feeding plastic material to and rearwardly through said chamber, a transverse substantially vertical ram, and means for longitudinally reciprocating said ram to pack earth around said tubular frame portion and thereby advance said frame.

15 9. A machine for forming a pipe in a trench, comprising a frame having a rearwardly projecting tubular portion, an inner form in said tubular portion cooperating therewith to define a tubular chamber and including a portion projecting rearwardly from said frame, a transverse substantially vertical ram plate, a transverse cam shaft journaled in said frame, means for rotating said shaft, longitudinal bars so arranged as to be shifted by said shaft and connected to said ram plate, said ram plate reciprocating longitudinally on said tubular frame portion to compact backfill therearound, and means for feeding plastic material through said chamber and compacting it around said inner form rearwardly of said frame.

20 10. In a machine for forming a pipe in a trench, 35 a frame, a hopper carried by said frame, a longitudinal tubular portion at the bottom of said frame projecting rearwardly therefrom and communicating with said hopper, a substantially vertical transverse ram plate bearing on said tubular portion rearwardly of said hopper, means carried by said frame for longitudinally reciprocating said ram plate to compact backfill deposited around said tubular portion, said plate and means advancing said frame as backfill is deposited therebehind, and an inner pipe form in said tubular portion and projecting rearwardly therefrom for shaping the interior of a pipe formed from material discharged from said hopper.

25 11. A machine for forming a pipe in a trench, 40 comprising a frame adapted to be advanced in said trench, an outer form carried by the bottom of said frame, a cylindrical inner form rotatably mounted within said outer form to define a tubular chamber therein, a helical feed member fixed to and encircling a portion of said inner form, means for feeding plastic material to said chamber, a shaft journaled longitudinally in said inner form, an unbalanced weight carried by said shaft within said form, means for rotating said inner form, and means for rotating said shaft and weight at higher speed than the speed of rotation of said inner form to vibrate said inner form.

30 12. A machine for forming a pipe in a trench, 45 comprising a frame having an outer form fixedly carried by and projecting rearwardly from the lower portion of said frame, a transverse substantially vertical ram plate above said outer form, means for longitudinally reciprocating said ram plate to compact backfill around said outer form, an inner form mounted within said outer form to define a tubular chamber therein, means for feeding plastic material to and through said chamber, and means for vibrating said inner form.

13. A machine for forming a pipe in a trench, comprising a frame having an outer form fixedly carried by and projecting rearwardly from the lower portion of said frame, longitudinally reciprocable ram means for compacting backfill around said outer form, an inner form journaled within said outer form to define a tubular chamber therein, a feed screw fixed to and encircling said inner form, means for supplying plastic material to said chamber, means for rotating said inner form, and means for vibrating said inner form.

14. A machine for forming a pipe in a trench, comprising a frame having an outer form fixedly carried by and projecting rearwardly from the lower portion of said frame, longitudinally reciprocable ram means for compacting backfill around said outer form, an inner form journaled within said outer form to define a tubular chamber therein, a feed screw fixed to and encircling said inner form, means for supplying plastic material to said chamber, means for rotating said inner form, and means for vibrating said inner form, said inner form including an elongated flexible, non-collapsible portion projecting rearwardly of said outer form.

15. A machine for forming pipe in a trench, comprising a frame adapted to be advanced in said trench and having an outer form in the lower portion thereof, an inner form rotatable in and projecting from said outer form and cooperating therewith to define a tubular chamber, means for feeding plastic material to and rearwardly through said chamber, said inner form having an opening therein intermediate the length thereof, means for feeding a flexible reinforcing member to and through said opening including an open ended passage extending axially of said inner form and curved at one end for registration with said opening, and means for rotating said inner form.

16. A machine for forming pipe in a trench, comprising a frame adapted to be advanced in said trench and having an outer form fixed in the lower portion thereof, a tubular inner form journaled at its forward end portion within said outer form and cooperating therewith to define a tubular chamber, means for feeding plastic material to and rearwardly through said chamber, a longitudinal open ended hollow shaft journaled in said inner form, an unbalanced weight fixed on said shaft, said inner form having an opening therein rearwardly of said shaft, means for feeding a flexible reinforcing member through said hollow shaft and thence laterally through said opening, means for rotating said inner form, and means for rotating said shaft.

17. A machine for forming a pipe in a trench, comprising a frame adapted to traverse said trench and having a longitudinal passage at its bottom defined in part by a rearwardly projecting tubular portion, a rotatable cylindrical form within said passage and cooperating therewith to

form a tubular chamber, means for rotating said form, an articulated cylindrical form trailing and providing a continuation of said cylindrical form, means reciprocating substantially horizontally for compacting earth around said rearwardly projecting frame portion as said frame advances, a feed screw in said chamber carried by said rotatable form, means for feeding plastic material to said chamber, and means for transversely vibrating said rotatable form.

18. A machine for forming pipe in a trench, comprising a frame adapted to traverse a trench and having an elongated longitudinal passage defined in part by a tubular portion projecting rearwardly from the lower portion of said frame, means reciprocating substantially horizontally for compacting earth around said passage as said frame advances, means for feeding plastic material to and rearwardly through said passage, an inner pipe form within said passage and including a uniform portion projecting rearwardly from said passage, said plastic material being discharged and shaped between said inner forms and said compacted earth rearwardly of said frame.

19. A machine for forming a pipe in a trench, comprising a frame adapted to traverse said trench and having a rearwardly projecting form at the lower portion thereof, longitudinally reciprocable means for compacting backfilled earth around said form, an inner form within said outer form and projecting rearwardly therefrom, means for discharging plastic material around said inner form rearwardly of said frame, and means for maintaining said frame upright in said trench.

20. A machine for forming a pipe in a trench, comprising a frame adapted to traverse said trench and having a rearwardly projecting form at the lower portion thereof, longitudinally reciprocable means for compacting backfilled earth around said form, an inner form within said outer form and projecting rearwardly therefrom, means for discharging plastic material around said inner form rearwardly of said frame, a vertical mast carried by said frame, and guy cables carried by said mast and anchored at points spaced from said trench for maintaining said frame and mast upright as said frame advances.

21. A machine for forming pipe in a trench, comprising a frame having an outer form in the lower portion thereof, an inner form rotatable in and projecting from said outer form and cooperating therewith to define a tubular chamber, means for feeding plastic material to and rearwardly through said chamber, means for feeding a reinforcing member into said chamber including a passage extending axially of said inner form with its forward end open to receive said member and terminating in a lateral portion opening through said inner form, and means for rotating said inner form.

HERMAN L. MOOR.
